TARGET ELECTRODE ASSEMBLY FOR AN ELECTRON DISCHARGE DEVICE

Robert B. Randels, Painted Post, N.Y., assignor to Westinghouse Electric Corporation, Pittsburgh, Pa., a corporation of Pennsylvania

Filed Mar. 15, 1963, Ser. No. 265,425

8 Claims. (Cl. 313—89)

This invention relates to an improved target electrode assembly and more particularly to an improved assembly in which an electric charge pattern or image is stored on a very thin dielectric member or membrane.

One particular application of this invention is within an image orthicon type pickup tube. The image orthicon tube consists of a photocathode onto which light from an input scene is directed and which emits electrons in response to the light. The photoelectrons are in turn accelerated and focused onto a thin dielectric target of a material such as glass. The energy of the electrons directed onto the dielectric storage target is sufficient to cause secondary emission from the dielectric target and thereby establish a potential pattern on the opposite side of the dielectric target representative of the visible image directed onto the photocathode. This pattern established on the opposite side of the dielectric target with respect to the photocathode is read out by an electron beam as is well known in the art to derive a video signal representative of the visible information directed onto the pickup tube. It is the customary practice to provide a fine mesh screen overlying or adjacent the dielectric target surface facing the photocathode for collecting the secondary electrons emitted from the dielectric target in response to bombardment by the photoelectrons.

In tubes of this type, the fine mesh screen collector electrode and the dielectric target are normally mounted together in a unitary target mesh assembly. The amount of spacing between the dielectric target and the collector mesh may vary in different tubes in order to obtain certain characteristics for particular applications. It is however desired that there be a uniform spacing between the dielectric target and the collector mesh over the entire surface. The normal spacing within the image orthicon is about 1 to 3 mils.

The dielectric target is normally of glass and is about 0.2 to 0.4 mil in thickness. Due to the manner in which the target is formed, it has been difficult in the past to provide a satisfactory target assembly in which the collector mesh is positioned at a uniform distance with respect to the dielectric target. The result of the non-uniform spacing is, of course, a variation in video signal intensity from one point to another as the glass target is scanned by the electron beam. The prior art practice of mounting the collector mesh and the dielectric membrane about their periphery resulted in similarities to a drum head mount. The tube, when subjected to mechanical vibration, exhibited rapid variations in capacity between the mesh and the membrane. This produced an unwanted modulation of the electrical signal output, not related to the charge pattern established on the membrane. This undesirable effect is referred to as microphonics. This problem is recognized within the industry and several solutions have been arrived at in an attempt to solve this microphonics problem. Most of these solutions have several disadvantages in the form of complexity, expense and creating other electrical problems.

It is accordingly an object of this invention to provide an improved electrode assembly.

It is another object of this invention to provide an improved target and mesh assembly which provides uniform operation over the entire target surface.

2

It is another object of my invention to provide an improved target and screen assembly which is substantially free from microphonics.

It is another object of my invention to provide an improved target and screen assembly to prevent microphonics due to physical forces applied to the tube.

In accordance with my invention, I provide a target assembly in which a thin spacer member having a substantially rectangular opening is provided between the collector mesh and the dielectric membrane. In addition, the spacer member provided between the collector mesh and the dielectric member is of such a construction as to provide a plurality of support surfaces for the membrane.

Further objects and advantages of the invention will become apparent as the following description proceeds. The features of novelty which characterize the invention will be pointed out in particularity in claims annexed to and forming a part of the description.

For a better understanding of the invention, reference may be had to the accompanying drawings, in which:

FIGURE 1 is a cross-sectional view of an image orthicon pickup tube embodying the teachings of my invention;

FIG. 2 is an exploded view of the target assembly structure embodied in FIG. 1;

FIG. 3 is a sectional view of the target assembly structure embodied in FIG. 1;

FIG. 4 is a face or front view of the target assembly embodied in FIG. 1;

FIG. 5 is an enlarged and sectional view of a portion of the target assembly taken along line V—V of FIG. 3;

Referring now to FIG. 1, there is illustrated an image orthicon pickup tube comprising an envelope 10 of a suitable material such as glass, having an enlarged or image section 12 at one end thereof. Within the other tubular portion 14 of the envelope 10, there is mounted a conventional image orthicon electron gun structure 16 for providing an electron beam of low velocity which is focused and accelerated by an anode electrode formed as a wall coating 18 on the inner surface of the envelope 10. A decelerating electrode 21 reduces the velocity of the electron beam so that it approaches a target assembly 39 including a thin glass target member 30 at practically zero velocity. An electromagnetic coil (not shown) surrounds the tubular envelope 10 and provides a focusing field aligning the electron beam perpendicularly to the surface of the glass target 30. A neck yoke (not shown) is also provided to provide a pair of scanning or deflecting fields perpendicular to each other and to the axis of the tube for causing the electron beam from the electron gun 16 to scan the surface of the glass target 30. The pairs of coils of the neck yoke are connected in appropriate circuits (not shown) which are provided with pulses as is well known in the art for furnishing the scanning magnetic fields.

The enlarged portion 12 of the envelope 10 is closed by a light transmissive face plate portion 20. A photocathode surface 22 is provided on the inner surface of the face plate 20. A scene, which is to be televised, is optically focused upon the photocathode surface 22 and causes the emission of photoelectrons from the photocathode 22 in proportion to the amount of light striking the elemental areas of the photocathode 22. The photoelectron emission from the photocathode surface 22 is focused on the target 30 by a magnetic field provided by a coil (not shown) around envelope 10 and the accelerating fields of electrodes 24 and 26. The photoelectrons are accelerated to such an extent that they strike the surface of a glass target 30 with sufficient energy to be above the first crossover potential of the target and create a greater number of secondary electrons than incident pri-

mary electrons. A fine collector mesh screen 40 is closely spaced from the surface of the glass target 30 and is maintained during the tube operation at a potential up to several volts positive relative to the cathode potential of the electron gun 16.

The low velocity electron beam of the electron gun 16 scanning the surface of the target 30 will bring the potential of the target to approximately that of the cathode of the gun. At this potential, the scanning electron beam will not land on the surface of the target 30 but will be electrostatically reflected back along the axis of the tube 10. The secondary emission caused by the bombardment of the target 30 by the photoelectrons from the photocathode 22 will cause the surface of the glass target 30 facing the photocathode 22 to charge in a positive direction so as to provide a positive charge pattern corresponding to the light image directed onto the photocathode 22. Due to the extreme thinness of the glass target 30, positive charges on the image side of the target will set up a corresponding positive potential pattern on the reading or the electron gun side of the target. As the electron beam from the gun 16 scans the surface of the target 30, electrons from the beam will be drawn to the positive areas of the target surface and will be deposited and will neutralize the positive potential pattern on the glass target 30. This will tend to charge the surface of the target 30 to cathode potential. The remainder of the beam unnecessary to return the surface of the target 30 to cathode potential will be reflected back toward the electron gun 16. The negative charges deposited on the gun side of the target 30 will unite by conduction through the glass target 30 with the positive charges on the photocathode side of the target 30. The electron beam from the gun 16 will be modulated by the removal of electrons deposited upon the surface of the glass target and in accordance with the positive charge pattern formed thereon. The modulated return beam is returned and will strike a first dynode 28 of a multiplier section surrounding the electron gun 16. This modulated return is then amplified by the multiplier sections and collected on a collector electrode which is in turn connected to any appropriate circuit to form the video signal. The above description is substantially conventional image orthicon operation and the applicant has described his invention incorporated in such a device in order to adequately explain and set forth the invention.

Referring now to FIGS. 2, 3, 4 and 5 for a more detailed description of the target assembly 39. The target assembly 39 is comprised of the collector electrode 40 and the glass membrane target 30. The collector 40 is comprised of a fine wire mesh 42 stretched across a circular aperture 44 provided in the annular mesh support ring 46.

The mesh 42 may be of a suitable material such as copper having a thickness of about 0.5 mil and having about 600,000 apertures per square inch. The support ring 46 may be of a suitable material such as an alloy of steel, iron and aluminum. The ring 46 includes a surface 43 facing the photocathode 22 which is substantially planar. The other surface 45 of the ring 46 includes an inner circular ridge or projection 47. An annular depressed surface 49 is positioned adjacent the rib 47 and on the same surface 45 of the ring 46 and extends completely around the ring 46. The mesh screen 42 is mounted on the support ring 46 by placing the peripheral edge of the mesh 42 over the depressed surface portion 49 and welding a weld ring 50 over the mesh 42 to the depressed surface portion 49. The weld ring 50 may be of stainless steel and is spot welded to the support ring 46. The remaining surface portion 51 of the surface 45 lies in about the same plane as the exposed surface of the weld ring 50. The rib 47 extends above this plane and the mesh 42 is stretched over the rib 47. The glass target 30 is also mounted or fixed at its edge on a support ring 32 with the ring 32 having an inturned flange 34 having a circular aperture 36 to which the glass membrane or storage film 38 is sealed. The ring 32 is of a suitable material such

as nickel iron and the technique of fabricating the glass and sealing to the ring is not a part of this invention and is well known in the art.

Positioned between the collector mesh assembly 40 and the glass target 30 is a spacer member 60 of a suitable material such as aluminum. The spaced member 60 is an annular disc-like member having a substantially rectangular aperture 64. The spaced 60 as indicated in FIGS. 3 and 4 is such as to provide an outer annular portion 62 lying in a first plane, an inner annular portion 66 having the rectangular opening 64 lying in a second plane parallel to said first plane with an interconnecting portion 68. The space between the first and second planes is about 5 mils. The spacer 60 is positioned on the surface 45 of the ring 46 as shown in FIG. 3 with the outer annular portion 62 in contact with one or both the surface portion 51 and the weld ring 50. The flange portion 34 of the target support ring 32 is in contact with the other surface of the outer annular portion 62. The annular interconnecting portion 68 lies between the inner edge of the flange portion 34 of ring 32 and the rib 47 of the ring 46. The assembly when clamped together by suitable clamping means utilizes the inner annular portion 66 and especially its edge 64 as the spacer means between the membrane 38 and the mesh 42.

The clamping means may consist of an outer clamp ring 70 provided with lugs 72, an annular resilient member 74 resting on the surface 43, an inner clamp ring 76 resting on the resilient member 74, and the lugs 72 which may be bent over to form an assembly as shown in FIG. 3. Other clamping means are known to those skilled in the art.

The spacer 60 may be formed using rubber die techniques from aluminum foil of about 1.8 mils in thickness. By using a foil of this thickness, it is found that a spacing of about 2.2 mils is provided between membrane 38 and the mesh 42. By forming the spacer 60 in this manner, a support is provided as illustrated in FIG. 5. This in effect provides a plurality of point supports for the membrane 38. In the specific embodiment shown, the aperture edges 64 of the spacer 60 form substantially rectangular aperture with smooth edges. It is possible to have an irregular edge to provide small tongues or projections extending inwardly. It is also possible to deform the area adjacent the edges to provide a plurality of support surfaces.

It is found that a spacer of a thickness of about 1.8 mils provides a wavy or undulating support surface with a plurality of support surfaces. The support surfaces alternate between the mesh 42 and the membrane 38. The points of support of the membrane 38 are separated by at least 15 mils.

The resulting structure provides a separation spacer between the membrane 38 and the collector mesh 42 such as to be substantially rectangular in shape and the dimensions of the rectangular opening 64 are slightly greater than the electron image directed onto the target 30 from the photocathode 22. The result of the rectangular shaped spacer is that vibrations of the tube when transmitted to the target will generate only high frequency modes which will be quickly damped out. The target glass 30 is stretched over the rounded shoulder of the spacer and rib 47. The random slight variations of the spacer 60 as shown in FIG. 5 from the perfect plane will produce points of contact to the target glass 38 and the mesh 42 and thereby form nodal points thus assuring that only very high harmonics of the fundamental vibration frequency can easily be excited. These high harmonics will be quickly damped out. If lower frequencies are excited, then these contact points will induce mode conversion and thus cause the vibration to be rapidly damped out.

While there has been shown and described what are at present considered to be the preferred embodiments of the invention, modifications thereto will readily occur to those skilled in the art. It is not desired therefore that the invention be limited to the specific arrangement

shown and described and it is intended to cover in the appended claims all such modifications as fall within the true spirit and scope of the invention.

I claim as my invention:

1. A target assembly for an electron discharge device comprising a target member including a supporting ring and a dielectric membrane supported thereon, a mesh electrode member including a support ring and a mesh supported thereon, a spacer member positioned between said target member and said mesh electrode, said spacer member in the form of an annular member having an outer periphery similar to said target member support ring and said mesh support ring, said spacer member having an inner periphery defining a substantially rectangular aperture of smaller area than the inner area of said target support ring, the inner periphery of said spacer lying just outside the active area of said target, said spacer member of a thickness of about 2 mils and having alternate support surfaces with respect to said mesh and membrane.

2. A storage target assembly for an electron discharge device comprising a target member including a support frame and a storage film supported thereon, an electrode member including a support frame and a grid supported thereon, an annular spacer member positioned between said target member and said electrode member, said spacer member including an outer portion positioned between said target support frame and said electrode member support frame and an inner portion forming a substantially rectangular opening, the edges of said opening having alternate spacing surfaces for said film and said grid.

3. An electrode assembly for an electron discharge device comprising a first member including an annular support member and a thin first electrode means supported thereon, a second member including an annular support member and a thin second electrode means supported thereon, a thin annular spacer member positioned between said first and second members, said spacer members having an inner substantially rectangular aperture, the edges of said aperture lying within the area defined by said annular support members, the area of said spacer adjacent the edges of said aperture bending with successive curves in alternate directions to provide in effect a plurality of alternate point support spacers between said first electrode means and said second electrode means.

4. A target assembly for an electron discharge device comprising a target member including a support ring and a membrane supported thereon, a mesh electrode member including a support ring and a mesh supported thereon, spacer means positioned between said target member and said mesh electrode, said spacer means providing a substantially rectangular opening with the portion of the surface adjacent the edges of said opening spacing said mesh and membrane, said surface being wavy in form to provide a plurality of alternate point support spacer surfaces between said membrane and said mesh.

5. A target assembly for an electron discharge device comprising a mesh electrode, a target electrode and a spacer member positioned therebetween, said mesh electrode comprising an annular support ring and a mesh secured to one surface of said support ring, said surface having an inner annular rib portion and said mesh secured to said surface exterior to said rib portion to stretch

said mesh over said rib portion, said target electrode comprising an annular support ring and a membrane secured to said support ring of said target electrode, said spacer member including an annular disc-like member having a substantially rectangular aperture therein, said spacer bending with successive curves in alternate directions about said aperture to provide a plurality of point supports for said mesh and membrane, and means clamping said mesh, spacer and membrane together to provide a discontinuous support for said membrane to suppress vibration in said membrane.

5 6. A target assembly for an electron discharge device comprising a mesh electrode, a target electrode and a spacer member positioned therebetween, said mesh electrode comprising an annular support ring and a mesh secured to one surface of said support ring, said surface having an inner annular rib portion, said mesh secured to said surface exterior to said rib portion and stretched over said rib portion, said target electrode comprising an annular support ring and a membrane secured to said support ring of said target electrode, said spacer member including an annular outer portion and an inner portion, said inner portion having a rectangular aperture therein, said inner portion of said spacer member positioned between said mesh and said membrane, said inner portion having an undulating surface for providing a spacer supporting said membrane by a plurality of points.

10 7. A target assembly for an electron discharge device comprising a mesh electrode, a target electrode and a spacer member positioned therebetween, said mesh electrode comprising an annular support ring and a mesh secured to one surface of said support ring said surface having an inner annular rib portion, said mesh secured to said surface exteriorly to said rib portion and stretched over said rib portion, said target electrode comprising an annular support ring and a membrane secured to one surface of said support ring of said target electrode, said spacer member including an annular disc-like member having an annular outer portion lying in a first plane and an inner portion having a rectangular aperture therein and lying in a plane parallel to said first plane, said inner portion separating and spacing said membrane and said mesh to provide a plurality of support points for said membrane.

15 8. A target assembly for an electron discharge device comprising a mesh electrode, a target electrode and a spacer member positioned therebetween, said mesh electrode comprising an annular support ring and a mesh secured to one surface of said support ring, said target electrode comprising an annular support ring and a membrane secured thereto, a thin annular disc-like member of about 2 mils in thickness having a rectangular aperture therein and having an undulating portion surrounding said aperture, said undulating portion separating said mesh and membrane by a distance of greater than 2 mils.
